UNITED STATES PATENT OFFICE

MELVIN C. INGE, OF ANAHEIM, CALIFORNIA

BLOW-OUT PREVENTER OR CONTROL HEAD

Application filed October 28, 1929. Serial No. 402,823.

This invention relates to a device for use in well drilling operations and relates more particularly to a blow out preventer or control head for controlling an oil or gas well.

In certain localities the gas pressures encountered in the drilling of wells are extremely high and often make it difficult and many times impossible to control the wells. As the pressures in such cases increase very rapidly, slow acting control devices are inadequate and ineffective in controlling the wells.

It is a general object of this invention to provide a control device or blow out preventer for a well, that is practical, dependable, and of improved construction.

Another object of the invention is to provide a well control device that is compact and simple of construction, which may be safely operated upon short notice.

It is another object of the invention to provide a fluid pressure actuated well control device that may be set or locked in the actuated or packing position.

A further object of the invention is to provide a device of the character mentioned that embodies packing arranged so that when it is set in position on an object, pressure from within the well tends to urge the packing into tighter engagement with the object.

It is a further object of the invention to provide a well control head of the character mentioned that occupies a minimum amount of space and may be operated from a point remote from the well.

An important object of the invention is to provide a control head for a well that includes a plurality of sections of packing that are operated by fluid pressure to simultaneously and with equal pressure engage or pack against a tool extending through the device.

A further object of the invention is to provide a blow out preventer that includes hydraulic or fluid pressure means for operating the packing and mechanical means for operating the packing that may be employed in the event the hydraulic means is for any cause inoperative.

Other objects and features of my invention will be best and more fully understood

from the following detailed description of a typical form and application of the invention, throughout which description reference is had to the accompanying drawings, in which:

Fig. 1 is a vertical detailed sectional view of the control head provided by this invention showing a well tool or drill string extending freely through it. Fig. 2 is a view similar to Fig. 1 showing the packing means in packing engagement with the tool. Fig. 3 is a horizontal detailed sectional view taken as indicated by line 3-3 on Fig. 2. Fig. 4 is an enlarged vertical detailed sectional view taken as indicated by line 4-4 on Fig. 2. Fig. 5 is an enlarged horizontal detailed sectional view taken as indicated by line 5-5 on Fig. 1, and Fig. 6 is an enlarged vertical detailed sectional view taken as indicated by line 6-6 on Fig. 1.

The control head or blow out preventer provided by this invention includes, generally, a body 10 to be applied to a well casing, packing means 11 carried by the body, fluid pressure actuated means 12 for operating the packing, and mechanical means A for operating the packing and for locking the packing in the set position.

The present device is intended to be mounted on the upper end of a well casing and is formed so as to allow various drilling tools to be passed in and out of the casing when the packing is retracted. In the drawings I have illustrated a portion of a coupling 13 threaded on to the lower end of the body 10 which may be considered as attached to the upper end of the well casing. I have shown a portion of a drilling string 14 extending through the body 10. The drilling string 14 is shown merely for purpose of illustration; it being understood that the device is operable to pack off around various other tools that may operate through the casing.

The body 10 is a substantially tubular member and may be attached to the upper end of a well casing by means of the coupling 13. The opening 15 of the body 10 is preferably proportioned to allow the insertion of the various tools into the well casing and is preferably concentric to the casing. In the

drawings I have shown the drill stem 14 extending through the body opening 15. In accordance with the invention the opening 15 is provided with a lateral recess or enlargement 16. The enlargement 16 may be at the central portion of the opening 15 and has outer sides or walls curved concentric with the axis of the opening 15. The lower end 17 of the enlargement may be flat and at right angles to the axis of the body. The upper end or wall 18 of the enlargement is of less width than the lower end 17 and an upwardly convergent face 19 is provided in the opening 15 at the upper edge of the enlargement. The face 19 is provided to slidably carry the packing means 11 and is substantially as long as enlargement 16.

The upper end portion of the body 10 may be externally threaded to receive a conduit, or the like. An annular chamber or cylinder 20 is provided in the upper end of the body 10. The cylinder extends longitudinally of the body and the side walls of the cylinder are curved concentric to the central longitudinal axis of the opening 15. The cylinder walls are finished to slidably carry a moving part. The cylinder 20 is closed at its upper end by an annular head 21 screw threaded into an enlargement 22 at the upper end of the cylinder. A suitable gasket 23 may be provided between the head 21 and the bottom of the enlargement to assure a fluid tight seal.

The packing means 11 is slidably carried on the convergent face 19 in the opening 15, and is adapted to form an annular assembly around the drill stem 14 to prevent the passage of fluid upwardly through the body 10. The packing means 11 includes a plurality of like sections 24 which, when assembled in packing engagement with the pipe 14, constitute a continuous annular body. In the particular form of the invention illustrated in the drawings there are four sections 24. The sections 24 are movable on the face 19 between the unactuated position adjacent the upper edge of the opening enlargement 16 and the actuated position adjacent the upper edge of the face 19. When the sections 24 are in the down or retracted position they are free of the opening 15 and do not interfere with the passage of tools through the body.

The sections 24 of packing may be laminated and may each consist of upper and lower metal plates 25 and 26, respectively, and a packing plate 27 arranged between the plates 25 and 26. The packing plates 27 may be formed of rubber, or the like, and may be retained between the plates 25 and 26 by bolts 28 extending completely through the sections. The packing plates 27 may be clamped between the metal plates so as to bulge or project from the sections 24 to effectively seat together and abut the drill pipe 14 and the face 19 to make an effective fluid

tight seal. The sides of the sections 24 are preferably radial to effectively seat together when in the actuated position. It is to be understood, of course, that the inner sides of the packing sections 24 may be formed or shaped to pack against any particular tool or part that may be run through the body 10.

The means 12 for actuating the packing sections 24 operates to move the sections simultaneously and with equal force or pressure. The means 12 is in the form of cylinder and piston means and includes, a piston 30 slideable in the cylinder 20, piston rods 31 connected to the piston and extending into the enlargement 16, and links 32 connecting the sections 24 of packing and the piston rods 31.

The piston 30 is annular in form and is provided to reciprocate in the cylinder 20. The piston 30 may have flat upper and lower sides and is proportioned to operate freely in the cylinder. Piston rings 30^a may be provided on the piston to cooperate with the walls of the cylinder. The invention provides means for admitting fluid under pressure, say steam, into either end of the cylinder to operate the piston 30 upward or downward. An opening or port 33 is provided on the lower end of the cylinder 20 which communicates with a conduit 34 and a port 35 is provided at the upper end of the cylinder in communication with a conduit 36. The passage of fluid through the conduits 34 and 36 may be controlled by a suitable fourway valve 37. It will be obvious that the conduits may extend to a remote point and that the valve 37 may be located at any suitable convenient point.

The piston rods 31 are connected to the piston 30 and extend through the lower end wall of the cylinder. There is preferably one rod 31 for each section 24 of packing and they may be symmetrically arranged around the central axis of the opening 16. The rods 31 may be screw threaded into openings in the piston and preferably extend parallel to the axis of the body 10. Suitable packing glands 37 are provided in the upper end of the enlargement 16 to pack around the rods 31.

The links 32 operatively connect the piston rods 31 and the sections 24 of the packing. The links 32 are pivotally attached to the lower ends of the rods and are pivotally connected with the lower plates 26 of the packing sections. A shaft or pivot pin 38 extends transversely through the lower end of each rod 31 and extends through yoked portions on the lower end of each link 32. A downwardly projecting lug 40 is provided on the lower side of the lower plate 26 of each packing section. Yoked portions on the upper ends of the links 32 are arranged at opposite sides of the lugs 40 and pivot pins 41 connect the yoked portions and the lugs.

With this construction the packing sections 24 are operatively connected with the piston 30 and are shifted along the face 19 upon movement of the piston 30 in the cylinder 20.

5 In accordance with the invention, means is provided to retain the sections 24 in engagement with the face 19. In the preferred form of the invention this means includes 10 leaf springs 42 attached to the bottom end 17 of the enlargement 16 and in pressure engagement with the inner sides of the links 32. The springs 42 project upwardly from the shoulder 17 and are provided with shoes 15 43 at their upper ends to slidably fit the inner sides of the links 32. The springs 42 urge the links 32 outward and thus insure the positioning of the sections 24 on the face 19.

20 In the preferred form of the invention the outward thrusts exerted by the springs 42 and by the engagement of sections 24 with a drill pipe 14, or the like, are transmitted from the sections, and links 32 to the body 25 10 by shoe projections 44 on the piston rods 31. There is preferably one shoe projection 44 provided adjacent the lower end of each rod 31 to slidably operate against the side walls of the enlargement 16 of the body opening. The projections 44 are preferably 30 directly in alignment with the pivot pins 38 so as to effectively transmit the outward pressure exerted on the pins to the walls of the body.

35 Means may be provided for setting the piston 30 in the up or actuated position. A screw 80 may be threaded through an opening in the body 10 so as to be operable to extend into the cylinder 20 and clamp against 40 the piston 30. A suitable packing gland 81 may be provided to pack around the screw 80.

45 As control heads of the class provided by this invention are generally used in emergencies and under adverse conditions, it is advantageous to provide auxiliary or secondary means for operating the packing means in the event the hydraulic or primary means for operating the packing fails or becomes inoperative. In the preferred form of the invention the auxiliary or secondary means is in the form of mechanical means and may be operated to shift the packing sections 24 into packing position when desired or necessary because of the lack of fluid under pressure to operate the fluid pressure means 12 or because of the inoperativeness of the means 12.

50 The mechanical means A for operating the sections 24 of packing includes, generally, a sleeve or nut 50 screw threaded on the exterior of the lower portion of the body and adapted to be rotated to move longitudinally of the body, and connections 51 between the 55 nut 50 and the piston rods 31. The nut 50

is preferably comparatively wide or extends a substantial distance longitudinally of the body and is threaded on to the body 10 by coarse, heavy threads. The threads are such as to cause the nut to be moved a maximum 70 distance longitudinally with a minimum of rotation. The exterior of the nut 50 is preferably curved concentric to the central axis of the body 10 and outwardly projecting flanges 75 52 are provided at the upper and lower edges of the nut. A cable or line 53 has one end attached to the exterior of the nut 50 and has a portion wound on to the nut. The line 53 may be operated by any suitable means. It will be seen that unwinding of the line 80 53 will cause rotation of the nut.

85 The connections between the nut 50 and the piston rods 31 include a tubular stem 54 normally in engagement with the lower end of each piston rod 31 and extending through 90 openings in the lower wall of the enlargement 16 of the opening 15. Packing glands 55 are provided in the openings to pack around the stems 54. The lower ends of the stems may be provided with yoked portions 56 between which are arranged rollers 57. The rollers 57 are rotatably carried on pins extending between the yoked portions 56. The rollers are provided to operate on the upper end of the nut 50 and an annular 95 groove 57^a may be provided in the upper end of the nut 50 to guide the rollers 57. A guiding part 58 projects downwardly from the lower end of each piston rod 31 and extends into a tubular stem 54. The guiding parts 100 58 are comparatively long so that they always remain in register with the openings of the stems 54. It will be seen from the above that the mechanical means A may be operated to lock the packing sections in position after 105 they have been shifted into the actuating position by the fluid pressure means 12.

110 It is believed that the operation of the device will be apparent from the foregoing detailed description. During normal drilling operations the parts are positioned as illustrated in Fig. 1. In this position the packing sections 24 are retracted so that they do not in any way interfere with the operation of tools through the body 10 and casing. When it is desired to operate the packing means with the fluid pressure actuating means 12 the valve 37 is operated to admit steam, or other fluid under pressure, into the lower end of the cylinder 20 through the port 33. The piston 30 is thus moved upward and the packing sections 24 are shifted to the position illustrated in Fig. 2 where they pack around the tool or drill pipe 14. If it is desired to lock the packing in this position the nut 50 may be rotated by operating the line 115 120 53 to bring the upper ends of the stems 54 into engagement with the lower ends of the piston rods 31. With the parts in this position, the steam may be exhausted from the 125 130

cylinder 20. It will be obvious that the mechanical means A may be employed to operate the packing sections 24 if desired or necessary. When it is desired to release the 5 packing means 11 the nut 50 is rotated to return it to the normal unactuated position and steam is admitted into the cylinder 20 through the upper port 35 to shift the piston downwardly to return the sections 24 to their 10 normal positions. The device may be constructed without the means A, as the remaining portions of the device constitute a complete and operative blow-out preventer.

Having described only a typical, preferred 15 form of my invention, I do not wish to limit myself to the specific details set forth, but wish to reserve to myself any changes or variations that may appear to those skilled in the art or fall within the scope of the 20 following claims.

Having described my invention, I claim:

1. A control device for use on a well including, a body to be connected to a well casing, the body having a passage extending 25 through it, a plurality of sections of packing in the body adapted to extend into the passage, and fluid pressure means for actuating the sections including a single annular piston within an annular cylinder in the body 30 surrounding the passage, and connections between the piston and the sections.

2. A control device for use on a well including, a body to be connected to a well casing, the body having a passage extending 35 through it, there being a convergent recess in the wall of the opening, a plurality of sections of packing slidably carried in the recess and adapted to extend into the passage, and fluid pressure means to actuate the 40 sections, including a single annular piston operable in an annular cylinder opening in the body surrounding the passage, piston rods attached to the piston, and links connecting the rods and sections.

45 3. A control device for a well including, a body to be connected to a well casing, the body having a passage extending vertically through it and having an annular cylinder opening surrounding the passage, packing 50 means carried in the body adapted to extend into the passage including a plurality of sections, and fluid pressure means for actuating the sections including a single piston in the cylinder opening and link connections between the sections and the piston.

55 4. A control device for a well including, a body to be connected to a well casing, the body having a passage extending vertically through it and having an annular cylinder 60 opening surrounding the passage, packing means carried in the body adapted to extend into the passage including a plurality of sections slidably in a convergent recess in the walls of the passage, and fluid pressure 65 means for actuating the sections including

a piston in the cylinder opening, connections between sections and the piston, and means for supplying fluid pressure to the cylinder at opposite ends of the piston.

5. A control device for a well including, a body to be connected to a well casing, the body having a passage extending through it, there being a convergent recess in the opening, packing means including a plurality of sections of packing slidably carried in the 70 recess, means for retaining the sections in engagement with the walls of the recess, and fluid pressure means for actuating the sections including a single piston operable in an annular cylinder opening in the body 75 around the passage, and connections between the sections and piston.

6. A control device for a well including, a body to be connected to a well casing, the body having a passage extending through it, 80 there being a convergent recess in the opening, packing means including a plurality of sections of packing slidably carried in the recess, spring means for retaining the sections in engagement with the walls of the 85 recess, and fluid pressure means for actuating the sections including a single piston operable in an annular cylinder opening in the body, and connections between the sections and the 90 piston.

95 7. A control device for a well including, a body adapted to be connected to a well casing, the body having a passage through it and a cylinder opening, packing means in the body including a plurality of sections of packing 100 operable to extend into the passage, fluid pressure means to operate the sections including a piston in the cylinder opening, rods attached to the piston, and links connecting the rods and section, and auxiliary means for 105 operating the sections to the extending position and to lock the sections in the extended position including a nut threaded on the body and stems extending between the nut and piston rods.

110 8. A control device for a well including, a body adapted to be connected to a well casing, the body having a passage through it and a cylinder opening, packing means in the body including a plurality of sections of packing 115 operable to extend into the passage, fluid pressure means to operate the sections including a piston in the cylinder opening, rods attached to the piston, and links connecting the rods and section, and auxiliary means for 120 operating the sections to the extended position and to lock the sections in the extended position including a nut threaded on the body, stems extending between the nut and the piston rods, and means for rotating the 125 nut.

9. A control device for a well including, a body adapted to be connected to a well casing, the body having a passage through it 130 and a cylinder opening, packing means in

- the body including a plurality of sections of packing operable to extend into the passage, fluid pressure means to operate the sections including a piston in the cylinder opening, 5 rods attached to the piston, and links connecting the rods and sections, and auxiliary means for operating the sections to the extended position and to lock the sections in the extended position including a nut 10 threaded on the body, stems extending between the nut and the piston rods, and means for rotating the nut, said means including a line around the nut.
10. A control device for a well including, 15 a body adapted to be mounted on a well casing, the body having a passage to register with the casing and having a convergent recess in the passage, packing sections operable to slidably cooperate with the recess to extend into the passage and seal about an object 20 therein, and means for actuating the packing section including a nut threaded on the body, stems operable by the nut, and links operatively connecting the stems and packing 25 sections.

In witness that I claim the foregoing I have hereunto subscribed my name this 15th day of October, 1929.

MELVIN C. INGE.
